UNITED STATES PATENT OFFICE.

AMI LECOULTRE PIQUET, OF BRASSUS, ASSIGNOR TO AGASSIZ FILS, OF ST. IMIER, SWITZERLAND.

STOP-WATCH.

SPECIFICATION forming part of Letters Patent No. 394,933, dated December 18, 1888.

Application filed October 19, 1886. Serial No. 216,641. (No model.)

To all whom it may concern:

Be it known that I, AMI LECOULTRE PIQUET, of Brassus, Switzerland, have invented certain new and useful Improvements in Chronograph-Watches, of which the following is a specification.

The object of my invention is to provide a new and improved stop-watch of simple construction which operates rapidly and accurately.

The invention consists mainly in a stop-watch having the wheel that engages with the stop-watch wheel and drives the stop-watch mechanism from the main works mounted on an oscillating shaft journaled in a fixed bridge and a shifting-lever.

The invention further consists in the novel construction of the mechanism for holding and locking the split-seconds mechanism, and in the arrangement of the stop-watch mechanism on the upper and lower surfaces of the three-quarter plate; and the invention also consists in the construction and combination of parts and details, as will be fully described and set forth hereinafter, and then pointed out in the claims.

In the accompanying drawings, Figure 1 is a back view of my improved stop-watch, parts being shown in dotted lines and others omitted entirely and others broken out. Fig. 2 is a cross-section on the line $x x' x^2 x^3 x^4$; Fig. 1. Fig. 3 is a detail cross-section on the lines $y y'$, Fig. 1. Fig. 4 is a detail cross-sectional view on the line $w w'$, Fig. 1.

Similar letters of reference indicate corresponding parts.

The wheel A , having three hundred teeth, is mounted rigidly on the tubular shaft or arbor A' some distance below the upper end, which arbor is passed through the works, and on the other end of said tubular shaft or arbor A' the fly-back hand A^2 is mounted, which can rotate over the dial I . With the wheel A the toothed wheel B , having thirty teeth, can be engaged, said wheel B being mounted on the upper end of the oscillating shaft B^2 , on the lower end of which the cog-wheel B' , having fourteen teeth, is mounted, said wheel B' engaging with the fourth wheel, C , of the usual watch-works. On the arbor C' of the wheel C , the usual small seconds-hand, C^2 , is mounted, which revolves over the small dial usually

provided on the large dial I . The oscillating shaft or arbor B^2 is mounted at its lower end to revolve and to rock, swing, or oscillate in the short bridge N , fastened by means of a screw on the upper surface of the main plate N' of the works, and acted upon by the spring N^2 , and the upper end of the said oscillating shaft B^2 is mounted to oscillate and at the same time to revolve in one end of the lever L , which is pivoted on the upper surface of the three-quarter plate L' to swing parallel to the same. The wheel A and the toothed wheel B are mounted in recesses of three-quarter plate L' .

The bridge N can be adjusted in position by means of the screw O , resting against one edge of said bridge and serving to press the bridge in the opposite direction of that in which it is pressed by the spring N^2 , and the pivoted lever L can be adjusted by means of the screw M , screwed into the three-quarter plate L' , and serving to limit the throw of said lever L .

Against that end of the lever L , opposite the one in which the shaft of the arbor is mounted, one end of the lever R rests, which is pivoted on the upper surface of the three-quarter plate to swing parallel with the same, the other end of said lever R resting against the rim of the toothed or star wheel F , which is fixed on the hub E' of the ratchet-wheel E , mounted to rotate on the under side of the three-quarter plate L' , parallel with the plane of the same, the hub E' of said wheel E passing through an aperture of the three-quarter plate, so that the toothed or star wheel F is upon the upper surface of said three-quarter plate L' . The wheel F has six teeth and the wheel E eighteen.

The hook-pawl P' , pivoted on one end of the lever P , engages with the teeth of the ratchet-wheel E , the opposite end of the lever P forming an eye through which the winding-stem and push-pin P^2 of the works can pass, so that the lever P can be operated by pushing the crown inward; but, if desired, the end of the lever P can be made independent of the winding-stem. A spring, P^3 , acting on the lever P , presses the end carrying the hook-pawl P' inward—that is, toward the center of the works.

The ratchet-wheel E is prevented from ro-

tating in the reverse direction by the locking pawl-spring Q, which can be adjusted by the screw Q'.

The spring L³, fastened on the top of the 5 three-quarter plate, rests against the lever L, between the pivot of the lever and the end in which the oscillating shaft P² is mounted, and presses that end of the lever L carrying the oscillating shaft toward the wheel A. A 10 heart-cam, D, is mounted rigidly on the tubular shaft or arbor A' directly above the stop-wheel A.

A lever, G, is pivoted on the top of the upper surface of the three-quarter plate, one end 15 of which lever is pressed against the edge of the heart-cam D by a spring, G', fastened on the upper surface of the three-quarter plate and acting on said lever G, said spring also 20 pressing a projection, G², of the lever G against the rim of the toothed or star wheel F. The lever H is pivoted on the upper surface of the three-quarter plate near the wheel A, and is provided at one end with a downwardly-projecting pin, H', which can engage with the 25 toothed rim of the wheel A. The other end of the lever H is pressed against the rim of the toothed or star wheel F by a spring, H², fastened on the top of the three-quarter plate and resting against the lever H, between the 30 pivot and the downwardly-projecting pin H', so that the said spring also serves for pressing the pin H' against the rim of the wheel A.

The above construction applies to stop-watches having a single fly-back hand. In 35 case a split-seconds hand, J', is provided, the same is mounted on a shaft or arbor, J, passed longitudinally through the tubular arbor or shaft A', and is journaled in a separate bridge, as shown in Fig. 2, carries at its upper 40 end the toothed wheel S, having two hundred and forty teeth, which wheel S is of less diameter than the wheel A. Said wheel S is provided with a pivoted arm, U', carrying a roller resting against the rim of a heart-cam, 45 T, mounted rigidly on the upper end of the tubular shaft or arbor A', which arm U' is connected by a link, V, with a spring, V², fastened on one end of the spokes of the wheel S, said spring serving to press the roller on 50 the end of the arm U' against the heart-cam T.

On the upper surface of the three-quarter plate two spring-levers, U, are pivoted adjacent to each other, the inner edges of the end 55 parts of which are toothed and are adjacent to the rim of the toothed wheel S. At diametrically-opposite points between said spring-arms a flat cam piece or finger, X', projects upward from the shaft X², mounted to turn in 60 the main plate N', which shaft X² carries a four-pointed star-wheel, X, directly above the main plate, which wheel X can be rotated by an angular lever, Z, pivoted at Z' and acted upon by a spring, Z². One end of the lever Z 65 projects beyond the edge of the works to permit operating it.

Y is a pawl engaged with a four-toothed

wheel, X, for preventing the reverse movement of the same, and Y' is a spring pressing the pawl Y against said wheel X.

70

Two spring-rods, d, are fastened at their lower ends in a plate, h, Fig. 2, and said spring-rods pass up through suitable apertures in the plates of the works and into apertures m of the two levers U and serve to 75 press said levers toward each other and their toothed ends toward the rim of the wheel S.

It will be observed that the elements of all the parts of the stop mechanism are fastened on the three-quarter plate, the most of them 80 on the upper surface of said plate, thus facilitating the attaching of said stop mechanism without interfering with the other parts of the works.

The operation is as follows: By pressing inward that end of the lever P at the winding-stem the pawl P' rotates the ratchet-wheel E

the distance of one tooth in a direction from right to left, thus causing one of the teeth of the star-wheel F to act on the projection G² 90

of the lever G, whereby the swinging end of said lever is removed from the heart-cam D on the tubular shaft A', whereby the wheel A is released at the same time that the end of the lever R, resting on the rim of the star-wheel F, drops into one of the recesses or notches of the said wheel and permits the

spring L³, which acts on the lever L, to throw that end of the lever L carrying the shaft B² toward the wheel A, whereby the wheel B is 100 engaged with the teeth of the wheel A. As

the wheel B' on the shaft B² is being continuously revolved from the fourth wheel, C, of the watch-works, the wheel A begins to revolve as soon as the wheel B' is engaged with 105 it.

The stop-watch mechanism is now in operation, and the hand A² is revolved over the dial. When this motion is to be stopped, that end of the lever P at the winding-stem is pushed inward, whereby the ratchet-wheel E 110

is again revolved the distance of one tooth and the wheel F is moved correspondingly. One end of the lever H slides off the rim of the wheel F into one of the notches, whereby 115

the downwardly-projecting pin H' is brought in contact with the rim of the wheel A, which is thus stopped immediately. At the same time the rim of one of the projections of the

wheel F acts on the lever R, the other end of which lever acts on that end of the lever L 120

opposite the one carrying the shaft B², whereby said shaft is swung from the rim of the wheel A and the wheel B is disengaged from the wheel A.

When the hand A² is to be brought back to twelve, the lever P is again pushed inward, whereby the ratchet-wheel E 125

is moved the distance of one tooth and the wheel F is rotated accordingly, whereby one of the teeth of the wheel F acts on the lever H and moves the pin H' from the wheel A, 130

which is thus released, and at the same time the projection G² of the lever G arrives at one of the notches or recesses of the wheel F, into which it drops under the action of the spring

G', whereby the swinging end of the lever G is pressed against the heart-cam, and, acting on the rim of the same, throws said heart-cam around until the end of said lever G rests in 5 the notch of the cam, whereby the hand A² is brought back to twelve.

The above operation relates to a watch having only one fly-back hand. When the wheel S is released, it is carried around by the heart- 10 cam T as the roller on the end of the arm U of the wheel S is held in the notch of said heart-cam T, which heart-cam is fixed on the tubular shaft or arbor A'. When the wheel S is locked in place, such movement cannot 15 take place. When it is desired to revolve the split-seconds hand J', the outwardly-projecting end of the lever Z is pressed inward, so as to revolve the wheel X from right to left, whereby the cam or finger X' is brought in 20 the position shown in Fig. 1 and forces the levers U U from each other, thus releasing the wheel S. The split-seconds hand J' is now revolved with the hand A². When it is desired to stop the split-seconds hand J', the projecting end of the lever Z is again pushed inward, whereby the star-wheel X is again turned one-quarter, and the finger or cam X' is brought into a position parallel to the line 25 drawn midway between the levers U, thus permitting the springs d to press the ends of the levers against the rim of the wheel S, which is thus locked in place. The heart-cam T continues to rotate, but cannot carry along the wheel S. When the lever Z is again pushed 30 inward, the levers U U are separated and the wheel S travels around the heart-cam until the end of the arm U' rests in the notch of said heart-cam T, whereby the hand J' is brought to the same position as the hand A².

Having thus described my invention, I claim 40 as new and desire to secure by Letters Patent—

1. A stop-watch constructed with an oscillating shaft or arbor so mounted that one end 45 only swings, said shaft or arbor carrying two wheels, of which the one on the upper or swinging end is capable of engaging with the stop-watch wheel A, and the other at or near the lower end of the shaft opposite the one 50 that swings is permanently engaged with one of the wheels of the works, substantially as shown and described.

2. A stop-watch having the wheel for engagement with the stop-watch wheel A mounted on an oscillating shaft or arbor, one 55 end of which is journaled in an adjustable bridge and the other in a movable lever, substantially as shown and described.

3. In a stop-watch, the combination, with 60 the usual watch-works, of an oscillating shaft or arbor mounted in a bridge and a pivoted lever, a toothed wheel on said arbor for engagement with the stop-watch wheel A, a cog-wheel on said shaft engaged with a cog-wheel 65 of the works, and a lever acted upon by a star-wheel and acting upon the pivoted lever in which one end of the oscillating arbor is

mounted, substantially as shown and described.

4. In a stop-watch, the combination, with 70 the stop-watch wheel A, of an oscillating shaft mounted in a bridge and in a pivoted lever, mechanism for shifting the pivoted lever, and a wheel on the oscillating shaft, which wheel can be engaged with the stop-watch wheel, substantially as shown and described. 75

5. In a stop-watch, the combination, with the stop-watch wheel A, of a star-wheel, mechanism for rotating the star-wheel, a locking-lever for the stop-watch wheel operated by the star-wheel, a heart-cam connected with the stop-watch wheel, a lever operated by the star-wheel and acting on the heart-cam, an oscillating shaft mounted on a bridge and a pivoted lever, a wheel on the oscillating shaft, which wheel can engage the stop-watch wheel, a cog-wheel on the oscillating shaft engaged with one of the wheels of the works, and a lever operated by the star-wheel and acting on the pivoted lever, in which one end of the oscillating shaft is mounted, substantially as shown and described. 85 90

6. In a stop-watch, the combination of an oscillating shaft carrying a wheel engaged 95 with a wheel of the works and a wheel for engagement with the stop-watch wheel A, a pivoted lever, in which one end of the oscillating shaft is mounted, and a check or adjusting screw at one side of the said pivoted lever, substantially as shown and described. 100

7. In a stop-watch, the combination of a bridge, a screw acting on the bridge, a spring serving to press the bridge against the screw, a pivoted lever, an oscillating shaft mounted 105 to revolve in the bridge and pivoted lever, a wheel on the oscillating shaft for engaging with one of the wheels of the watch-works, and a wheel on the other end of the shaft for engaging with the stop-watch wheel, substantially as shown and described. 110

8. In a stop-watch, the combination, with the toothed wheel, of two pivoted levers, one at each side of the same, two spring-rods fastened in a suitable plate and projecting 115 upward and through said levers and pressing them toward each other, and a cam-piece for pressing the levers from each other, substantially as shown and described.

9. In a stop-watch, the combination, with a toothed wheel, of two spring-levers, one pivoted at each side of the wheel, springs fastened below the levers and projecting upward and acting on said levers, and a cam for separating the levers, substantially as shown and described. 120 125

In testimony that I claim the foregoing as my invention I have signed my name in presence of two subscribing witnesses.

AMI LECOULTRE PIQUET.
